G. W. DRIGGS.
BALING PRESS.

2 Sheets—Sheet 2.

No. 498,845.

Patented June 6, 1893.

UNITED STATES PATENT OFFICE.

GEORGE W. DRIGGS, OF ELYRIA, OHIO, ASSIGNOR OF ONE-HALF TO MOSES BEAL, OF SAME PLACE.

BALING-PRESS.

SPECIFICATION forming part of Letters Patent No. 498,845, dated June 6, 1893.

Application filed July 11, 1892. Serial No. 439,696. (No model.)

To all whom it may concern:

Be it known that I, GEORGE W. DRIGGS, of Elyria, in the county of Lorain and State of Ohio, have invented certain new and useful 5 Improvements in Baling-Presses; and I do hereby declare the following to be a full, clear, and exact description of the invention, such as will enable others skilled in the art to which it pertains to make and use the same.

10 My invention relates to improvements in baling-presses, more especially designed for baling hay, the object being to produce a baling press that is simpler in construction, less expensive, more durable, and more efficient 15 than the presses of the variety indicated that have heretofore been devised.

With this object in view, my invention consists in certain features of construction and combination of parts, hereinafter described 20 and pointed out in the claims.

In the accompanying drawings, Figure 1 is a side elevation, partly in vertical section on line 1—1, Fig. 2, of so much of a baling-press as is considered necessary to show in order to 25 illustrate my invention. Fig. 2 is a plan, partly in section, of the mechanism employed for reciprocating the compressing-plunger. Fig. 3 is a perspective in detail.

A represents the inclosing casing or frame- 30 work endwise whereof reciprocates the compressing-plunger, B, and C represents a hopper at which the hay or material to be baled is fed in advance of plunger B.

D represents a right and left-handed screw, 35 that, at the forward end, terminates in a plain portion d to the forward extremity whereof plunger B is operatively connected in such a manner that screw D will rotate without rotating the plunger. Screw D, at the rear end 40 of plain portion d , has bearing in the hub of bevel-gear E to which the screw is rotatably connected preferably by the well known means of groove and feather, as at e, the groove being formed in section d of the screw 45 and being of sufficient length to accommodate the full stroke of the screw. Gear E has suitable bearing in partition a of the frame-work or casing A, and is driven by a pinion F operatively mounted on driving-shaft f, the arrow indicating the direction of rotation of said 50 shaft.

D' D² represent, respectively, the right and left-handed sections of screw D, and a' a² represent uprights or partitions located a suitable interval apart as will hereinafter more fully appear and perforated, as at a³, respectively, to permit screw D to freely reciprocate therethrough.

G represents a follower wherein the rear end of screw D has bearing, said follower being 60 adapted to move, in unison with the screw, and endwise suitable guides or ways G' rigid with the supporting-structure. Just forward of follower G the screw has an annular shoulder or collar d' preferably integral therewith and just rearward of the follower the screw has loosely mounted thereon a collar, d², that, together with the follower is held in place upon the screw by means of shoulder or collar d' aforesaid and a collar, d³, rigidly mounted at 70 the rear of loose collar d².

H H' represent two pairs of sliding blocks secured, respectively, to uprights or partitions a' a², blocks H being located at opposite sides of the right-hand section of the screw and blocks H' being located at opposite sides of the left-handed section of the screw. Pairs of blocks H H' are substantially the same in construction, a pair being shown detached in 75 Fig. 3, the blocks being slotted, as at h, for the passage of bolts h', that secure the blocks to their respective supports a' a², and the blocks being screw-threaded on their inner sides, that is, on the sides adjacent screw D, right or left-handed to correspond with the 80 threads of the respective threaded sections of screw D, the threads of blocks H being adapted to engage the threads of section D' and the threads of blocks H' being adapted to engage the threads of section D². The sliding-blocks H H' on one side of screw, D, are provided with upright studs or pins h² that engage elongated slots I' in plates I pivoted, as at I², to the sliding-blocks at the opposite side of screw D. Plates I are operatively connected with each other by means of a link J that is provided with a laterally and outwardly-projecting arm or member, J', adapted to be engaged by dogs or projections g' g², of 85 forwardly-extending arm g of follower G. 90

The reciprocation of screw D is effected by the mechanism just described. The draw- 95

100

ings exhibit the parts in position at the commencement of the rearward stroke of the screw and connected compressing plunger, when studs or pins h^2 are in engagement with the rear end of slots I' in plates I and dogs or projections g', g^2 are at the extreme of their forward movement, dog or projection g^2 being still in engagement with the lateral arm of link J .

10 One or the other pair of sliding-blocks is always in engagement with screw D and in the position of parts shown blocks H' are in engagement with the screw while blocks H are out of engagement with said screw. The 15 rotation of screw D being in the direction indicated by the arrow, it follows that during the rotation of said screw while left-handed threaded blocks H' are in engagement with the correspondingly threaded section of the 20 screw, the screw and connecting plunger B will be receded to permit the feeder to deliver another batch of hay or material to be baled within the range of the plunger.

The arrangement of parts is such that at 25 the extreme of the rearward movement of screw D , dog or projection g' will come into engagement with the laterally-projecting arm or member J' of link J and cause the latter to be actuated to oscillate plates I rearward 30 and the trend of slots I' in said plates is such that during the rearward oscillation of the plates, blocks H, H' , by means of studs or pins h^2 , will be simultaneously moved into and out of engagement with screw D , respectively, and blocks H being adapted to engage the right-handed screw-threaded section of the screw, the screw will thereupon be reciprocated in the opposite direction to advance plunger B to compress the batch of hay or 35 material delivered before it. The screw having reached the extreme of its forward movement dog or projection g^2 will engage lateral arm or member J' of link J and cause the return of blocks H, H' to the position shown, 40 throwing blocks H out of engagement and blocks H' into engagement with the screw as indicated.

The screw-threads of screw D and blocks H, H' are of the ratchet variety; the threads 45 should have a coarse pitch, preferably about an inch; the length of the screw-threaded sections of the screw should be such as to sufficiently accommodate the full stroke of the screw, and dogs or projections g', g^2 should be located such a distance apart that they will 55 engage lateral arm J' of link J at the proper time.

The mechanism hereinbefore described for 60 operating compressing plunger B , it will be observed, is not only exceedingly simple in construction, and comparatively inexpensive, but is durable and not liable to get out of order.

Another important feature of my invention 65 consists in the connection of the feeder operatively with reciprocating-screw D .

Referring to Fig. 1 of the drawings, K rep-

resents the feeder that is adapted to deliver hay in advance of the compressing plunger. Feeder K is attached to the one end of a tilting-lever L pivoted, as at l , to an upright or standard a^3 rigid with the supporting-structure or casing A . To the opposite end of said lever is pivotally connected a rod or link M , the other extremity whereof is pivoted to an upwardly-projecting ear or pair of ears of collar d^2 on screw D . By the construction just described it will be observed that as screw D and connected plunger B recede lever L , by means of connecting rod or link M , 70 will be actuated to depress feeder K and cause the latter to feed a batch of hay or material in advance of the receding plunger, and as the plunger advances to act upon the material thus delivered within its range, feeder 75 K will be elevated out of the way to permit another batch of material to be delivered into hopper C .

From the foregoing it will be observed that 80 by means of a press embodying my improvements the material can be baled with the greatest facility and dispatch.

N represents a bar designed to more effectively support and steady the feeder, the same being secured to the feeder at one end, pivoted to upright or standard a^3 at its opposite end, and arranged parallel with the tilting-lever L .

What I claim is—

1. In a baling-press, in combination, the 100 compressing-plunger, a right and left-handed screw connected with the plunger substantially as described, a pair or set of screw-threaded blocks, adapted to engage the right-handed section of the screw, and a pair or set 105 of screw-threaded blocks adapted to engage the left-handed section of the screw and suitable mechanism for simultaneously moving or sliding the right and left-handed threaded-blocks in opposite directions, respectively, 110 into or out of engagement with the respective threaded sections of the screw, substantially as and for the purpose set forth.

2. In a baling-press, in combination, the 115 compressing-plunger, a right and left-handed screw connected with the plunger, substantially as described, two pairs of screw-threaded blocks, H, H' , adapted to engage, respectively, the right and left-handed sections of the screw and the blocks of a pair being located at opposite sides of the screw, mechanism 120 for simultaneously actuating said blocks, the one pair of blocks into and the other pair of blocks out of engagement with the respective threaded sections of the screw, substantially as and for the purpose set forth.

3. In a baling-press, in combination, the 125 compressing-plunger, a right and left-handed screw connected with the plunger substantially as described, two pairs of screw-threaded blocks, H, H' , adapted to engage, respectively, the right and left-handed sections of the screw, the blocks of a pair being located 130 at opposite sides of the screw, mechanism for

simultaneously actuating said blocks, the one pair of blocks into and the other pair of blocks out of engagement with the respective threaded sections of the screw, and comprising the following elements:—a pair of plates, I, pivoted to the blocks at one side of the screw and slotted as at I', studs or pins rigid with the other blocks and engaging slots I', a link J connecting said plates and provided with an arm or projecting member, J', and an arm or member g, connected and adapted to reciprocate with the screw and provided with dogs or projections, g, g², the arrangement of parts being substantially as and for the purpose set forth.

4. In a baling press, the combination with a compressing plunger, and a rotary right and

left handed screw, of screw threaded sliding blocks adapted to engage respectively the right and left handed screws, studs or pins, 20 plates having slots therein into which said studs or pins project, link J with arm or projecting member thereon, a follower, an arm on the follower provided with dogs or projections in position to engage the projecting 25 member on link J, substantially as set forth.

In testimony whereof I sign this specification, in the presence of two witnesses, this 31st day of May, 1892.

GEORGE W. DRIGGS.
